United States Patent Office

Des. 182,806

Patented May 20, 1958

182,806

WASTE RECEPTACLE OR SIMILAR ARTICLE

Harold Gleitsman, New Rochelle, and Carl Fuerst, Bronx,
N. Y., assignors to Gleitsman's, Inc., Long Island City,
N. Y., a corporation of New York

Application July 22, 1957, Serial No. 47,024

Term of patent 14 years

(Cl. D58—17)

FIG. 1

FIG. 3

Fig. 1 is a front elevational view of a waste receptacle or similar article showing our new design;

Fig. 2 is a side elevational view thereof; and

Fig. 3 is a top plan view thereof.

The rear and side not shown are the same as the front and side, respectively, shown.

We claim:

The ornamental design for a waste receptacle or similar article, substantially as shown and described.
